UNITED STATES PATENT OFFICE.

JOHN C. STOKES, OF SHREVEPORT, LOUISIANA.

DRILL.

1,360,328.

Specification of Letters Patent. Patented Nov. 30, 1920.

Application filed December 20, 1919. Serial No. 346,273.

To all whom it may concern:

Be it known that I, JOHN C. STOKES, a citizen of the United States, residing at Shreveport, in the county of Caddo and State of Louisiana, have invented certain new and useful Improvements in Drills, of which the following is a specification.

This invention relates to well digging apparatus, and the primary object of the invention is to provide an improved drill having means for changing the drill bits in a deep well, without necessitating the withdrawal of the drill stem or pipe from the hole.

Another object of the invention is the provision of an improved means for expanding the drill bits, after the same have reached a pre-determined position in relation to the drill stem or pipe, and for holding the bits in their extended positions against accidental displacement.

A further object of the invention is to provide an improved means for connecting the drill bit to the drill holder, so that the drill holder will engage the bit in such a manner that the weight thereof will effectively hold the bit in extended position and brace the same so as to prevent breakage thereof when the same strikes a rock or boulder.

A further object of the invention is to provide a sectional bit, which when in its extended position will be identical in form with the usual solid fish tail bit now in vogue, which has been found to give the best results in deep well boring.

A still further object of the invention is to provide an improved bit holder having means formed therein for effectively washing the curved terminals of the bit sections, so as to remove the debris from around the same during the drilling operation.

A still further object of the invention is to improve the construction of the tool holder or bushing so as to effectively brace the bit sections when the same are in their extended positions, so as to prevent the breaking of the bits when the tool is in operation.

A still further object of the invention is to provide an improved device of the above character which is of exceedingly simple and durable construction, one which will be easy to manufacture, and one which can

be placed upon the market at a reasonable cost.

Other objects of the invention will appear in the following detailed description taken in connection with the drawings, forming a part of this specification, in which drawings:

Figure 1 is a longitudinal vertical section through the improved drill apparatus.

Fig. 2 is an enlarged fragmentary section showing the drill bit holder in its raised position, and the bits in their collapsed relation.

Fig. 3 is an enlarged vertical longitudinal section taken at right angles to Fig. 1, and showing the bit holder and bits in their raised position.

Fig. 4 is a detail transverse section taken on the line 4-4 of Fig. 1.

Fig. 5 is a detail transverse section taken on the line 5-5 of Fig. 3.

Fig. 6 is a detail vertical longitudinal section taken on the line 6-6 of Fig. 1.

Fig. 7 is a detail transverse section through the tool holder or bushing taken on the line 7-7 of Fig. 3, and

Fig. 8 is a bottom plan view of the tool holder or bushing, showing the bits in their extended operative positions.

Referring to the drawings, in detail, wherein similar reference characters designate corresponding parts throughout the several views, the letter A indicates the improved device which includes the stem B, the tool holder C, the bit carrier D, the bit E and the hoisting cable F for the bit carrier. The stem B is made up of the usual pipe sections 10 of the desired diameter connected together in the usual manner. The uppermost pipe section 10 has rotatably connected thereto the cap 11 by the usual or any preferred coupling 12, and the cap is provided with a hanger 13 and hose 14. Any standard rig (not shown), cap, hanger, hose connection and ferrule can be used with the improved drill. The lowermost pipe section 10 has threadably connected thereto the bushing or tool holder C.

The bushing or tool holder C includes a tubular body 15 having its upper end provided with internal threads 16, for the reception of the lower threaded end of the lowermost pipe section 10 as heretofore stated, and the body 15 directly below the

screw threads 16 is provided with an internal annular shoulder 17, which forms means for limiting the downward movement of the bit E in the holder, and for forming an 5 abutment for preventing the upward movement of the bit E, when the same is in operative position. The bore of the tubular body 15 below the annular shoulder 17 is gradually increased in diameter as at 18 10 toward its lower end so as to permit the expansion of the bit E. The inner surface 18 of the lower portion of the bore is provided with oppositely directed grooves 19 and outwardly projecting shoulders 20 to 15 prevent the twisting of the bit E in the tool holder, when the bit is in operative position. The internal diameter of the shoulder 17 is just sufficient to accommodate the bit carrier D and the shoulder forms a guide for 20 the same.

The carrier D includes a cylindrical heavy solid body 21 and the same is arranged to slide longitudinally of the stem B and is provided with a pair of spaced depending 25 legs 22, which may be formed integral of the body or shown secured thereto by bolts 23. When the legs 22 are made separate from the body 21, the opposite sides of the body at the lower end thereof are provided 30 with notches 24 for the reception of the upper ends of the legs 22, and the notches form means whereby the outer surfaces of the legs will extend flush with the outer surface of the body 21. The lower terminals of the 35 legs 22 are tapered as at 25, so as to facilitate the centering thereof. The legs 22 form means for supporting the bit E, which is arranged between the legs.

The bit E includes a pair of independent 40 blades 26 which are constructed identical with one another and each includes a relatively long elongated flat body having its lower end beveled upwardly and inwardly toward the other as at 27, and the outer ends 45 of the beveled portions are struck outwardly in opposite directions to provide curved biting points 28. The bit E, when in its extended position, as shown in Fig. 1, is similar to the ordinary type of fish tail bit which 50 has been found to be the most serviceable for deep well boring. The upper terminals of the blades 26 have their outer edges provided with outwardly projecting shoulders 29, which are provided with inwardly extending notches 30, which extend inwardly 55 at an angle to the horizontal axis of the blades, and the notches form means for engaging the annular shoulder 17 formed on the tool holder or bushing D. Each of the 60 blades 26 below the transverse axis thereof is provided with an arcuate slot 31, which extends downwardly from the longitudinal axis of the blade toward the side edge thereof, and the lower end of the slot 31 terminates in a relatively short straight portion 65

32 which extends parallel with the side edge of the blade. The slots 31 slidably receive the transversely extending bolt 33, which is carried by the lower terminals of the legs 22. When the weighted body 21 is being raised 70 the bolt 33 rides to the upper portions of the slots 31 and tends to draw the blades toward each other, but when the weighted body 21 is in its lowered position, the pin 33 tends to ride toward the lower ends of the 75 slots and expand or force the blades 26 outward in opposite directions.

The lower ends of the legs 22 at the opposite sides thereof are provided with longitudinally extending bores 35, formed in the 80 legs, which in turn communicate with inwardly extending openings 36 formed in the upper ends of the legs, and these openings and bores, form means whereby the water, soft mud, or other bit cleaning fluid can be 85 forced through the bit holder and against the terminals of the bits for removing the material cut by the bits, away from the points thereof.

The upper end of the weighted body 21 90 of the bit carrier D is provided with a central threaded socket 37, which receives the coupling 38 of the hoisting cable or rods F.

The hoisting cable or rods F include a plurality of sections 39 which correspond to 95 the pipe sections 10 and each time a pipe section is added to the stem, a section is added to the cable or rods.

When it is desired to put a bit E in the tool holder C, while the same is in the ground, 100 the tool holder is raised high enough from the bottom of the well to permit the bit E to be lowered into place as is shown in Fig. 1 of the drawings. This is accomplished by hoisting the entire drill stem B by the hanger 105 13 to the desired height. The stem B is then clamped or held in this position and the cap 11 removed, which permits the bit E and carrier D to be lowered into the same by means of the cable F.

During the lowering of the bit E in the 110 stem B, the same hangs on the bolt 33 and owing to the formation of the slots in the bit blades 26, the same are closed together as the blades of a pair of scissors. When the 115 bit E reaches the tool holder and bottom of the well, the extended top edges 29 of the blades 26 catch on the upper edge of the shoulder 17, and prevent the blades from being lowered any farther. The weight of 120 the bit carrier 21 forces the bolt 33 down to the lower ends of the slots 31 which forces the blades 26 to expand in the bottom of the tool holder C and in so doing each bit locks under the shoulder 17 owing to the formation of the notches 30.

During the expansion of the blades 26, the same may engage anywhere against the inclined wall 18 of the tool holder C or drop at once into the slots 19 and against the 130

- shoulders 20. If the blades 26 do not drop at once into their places, they will remain against the walls 18 until they are lowered to the bottom of the well and the tool holder 5 begins to revolve, and when anything strikes the bit it will have a tendency to hold the same, and the same remains stationary until the tool holder touches them, at which time the weight of the tool holder C and bit carrier D will force the blades 26 into the slots 19 and against the shoulders 20. When the whole tool is revolving, the bits A will have a tendency to brace one another in the center of the tool holder. The drilling is done 10 in the usual manner, and the water or mud and water that has come down the drill stem, to remove the debris from the bottom of the well passes from the pump through the hose 14, through the perforated cable holder 40 which will be hereinafter more fully described down the drill stem B through the 15 openings 35 and 36 to the bottom of the well and up the outside of the drill stem B to the surface of the ground.
- 20 25 When it is desired to remove the drill bit E from the stem the same is raised in the manner heretofore described, and the cap removed, after which the cable F is pulled upwardly which forces the bolt 33 to the upper 30 ends of the slots thus collapsing the blades 26 of the bit E and thus permitting the same to be easily pulled out of the stem.
- The perforated cable holder 40 is of disk 35 shape and is provided with a slot 41 to hold the cable F in position when the last cable section is placed in position. The upper terminal of the last cable section is provided with the coupling 42 which prevents the upper end of the cable from slipping out of the 40 slot 41. This plate or cable holder 40 can be placed in any joint of the drill stem B. It is so constructed that the same will fit the end of a section of the drill pipe B, and at the same time allow the section to be fitted 45 into the coupling or pipe cap.
- From the foregoing description it can be seen that an improved drill is provided of exceptionally durable and simple construction, which will permit the drill bit to be 50 changed, without necessitating the removal of the entire drill stem.
- Changes in details may be made without departing from the spirit or scope of my invention; but,
- 55 I claim:
1. A drill comprising a tool holder, a sectional bit, and means slidably and pivotally carrying the bits arranged to open and close the same in relation to each other.
  2. A drill comprising a stem, a tool holder carried by the stem, a bit carrier, a support on the carrier, a bit including a pair of sections slidably and pivotally mounted on said support.
  3. A drill comprising a stem, a tool holder

carried by the stem, a bit carrier, a transversely extending bolt arranged on the carrier, and a bit including a pair of sections slidably and pivotally mounted on said bolt.

4. A drill comprising a stem, a tool holder 70 carried by the stem, a bit carrier including a solid weighted body and a pair of depending spaced legs, a bolt extending transversely across and carried by the legs, and a bit including a pair of blades slidably and 75 pivotally mounted on said bolt.

5. A drill comprising a stem, a tool holder carried by the stem, a bit carrier including a heavy body and a pair of depending spaced legs, a bolt carried by the legs and 80 extending transversely across the same, a pair of bit blades slidably and pivotally mounted on said bolt, and outwardly extending shoulders formed on the upper terminals of the bit blades, arranged to engage the 85 tool holder when the same reaches a predetermined position.

6. A drill comprising a stem, a tool holder carried by the stem, a bit carrier arranged in the holder, a pair of bit blades having 90 slots formed therein below the transverse axes thereof mounted in said holder, and a bolt carried by the bit carrier fitted in said slots arranged to slidably and pivotally support said blades.

7. In a drill, a drill carrier, a pair of relatively long bit blades having slots formed therein arranged entirely below the transverse axes thereof, and a bolt carried by the carrier positioned in said slots arranged to 100 slidably and pivotally support said blades.

8. A drill comprising a stem, a tool holder, a bit carrier slidably mounted in the stem and holder including a solid body, and a pair of depending spaced legs, bit blades 105 slidably and pivotally carried by the legs of the carrier, the legs of the carrier having longitudinally extending bores therethrough terminating adjacent to the lower ends of the bit blades.

9. A drill comprising a stem, a tool holder carried by the lower end of the stem having an inwardly extending annular shoulder formed therein, a bit carrier slidably mounted in the stem and holder, the inner face of 115 the holder below the shoulder being provided with an outwardly flared face, bit blades pivotally and slidably carried by the carrier, and having outwardly projecting extensions formed on their outer edges adjacent to their upper ends arranged to engage the shoulder, the blades having inwardly extending inclined notches formed therein opposite to said projecting portions arranged to engage the shoulder.

10. A drill comprising a stem, a tool holder carried by the stem, a bit carrier slidably mounted in the stem and tool holder, said tool holder having an internal annular shoulder, the bore of the tool holder below 130

the shoulder, being flared downwardly and outwardly, said flared portion of the bore being provided with longitudinally oppositely disposed grooves and shoulders, and 5 bit blades pivotally and slidably carried by the carrier, means formed on the upper ends of the bits arranged to engage the shoulder of the tool holder to prevent downward movement thereof, the outer edges of the blades being arranged to engage in the 10 grooves and longitudinally extending shoulders when the blades reach their lowermost positions.

JOHN C. STOKES.
